HOOKLESS SLIDE FASTENER

Samuel J. Lackritz, New York, N. Y., assignor to
 Kee Zipper Corporation, New York, N. Y., a
 corporation of New York

Application December 1, 1949, Serial No. 130,409

4 Claims. (Cl. 24—205.14)

1

This invention relates to a new and improved hookless fastener device, including a new and improved slide for hookless fasteners. It also relates to an improved method of assembling the parts of the slide.

This application is a continuation-in-part of my prior U. S. applications, Serial No. 668,678, filed May 10, 1946, for Slide for Hookless Fasteners, now matured into Patent No. 2,590,106, dated March 25, 1952 and Serial No. 55,480, filed October 20, 1948, for Hookless Fastener Device now matured into Patent No. 2,590,107 dated March 25, 1952. Reference is also made to a co-pending U. S. application under common ownership, Serial No. 93,791, filed May 17, 1949, for Unlockable Slide for Hookless Fasteners, now matured into Patent No. 2,607,976 dated August 26, 1952, the inventor's name being Alex Zahel.

In using a hookless fastener, the interlockable hookless fastener devices are frequently jammed or obstructed by a thread or piece of cloth of the garment or other article in which hookless fasteners are used.

According to this invention, the longitudinal walls of the slide are sufficiently separable to pass over the obstruction so that the release member of the slide can disengage the interlocked hookless fasteners at the jam or obstruction, while said jaws remain operative to interlock the hookless fasteners when the slide is moved in the longitudinal locking direction.

The improved slide can be made and assembled at very low cost.

The invention is further explained in the annexed description and drawings, which disclose a preferred embodiment.

Fig. 1 is a top plan view of the improved slide, showing the pull member in horizontal longitudinal position. The longitudinal walls of the slide are in normal or selected proximate position;

Fig. 2 is a top plan view of the slide, similar to Fig. 1, with the pull-member and transverse pin removed;

Fig. 3 is a slide elevation of Fig. 1;

Fig. 4 is a section on the line 4—4 of Fig. 1;

Fig. 5 is similar to Fig. 4, showing the pivot axis of the pull-member longitudinally disposed and showing the transverse pin moved to the release position so that the longitudinal walls of the slide are inclined to each other in selected separated positions, in order to provide the necessary clearance for enabling said longitudinal walls to pass over an obstruction or a jammed part of the hookless fasteners;

Fig. 6 is a section on the line 6—6 of Fig. 3, partially in plan view;

2

Fig. 7 is a section on the line 7—7 of Fig. 1; Fig. 8 is an elevation of the transverse pin; Fig. 9 is a bottom plan view of Fig. 8; Fig. 10 is a perspective view of the transverse

5 pin;

Fig. 11 is a side elevation of the pull-member; and

Fig. 12 is a bottom plan view of Fig. 11.

The body of the slide is made by bending a 10 planar blank of sheet metal to provide a bottom or longitudinal wall 1 and a top longitudinal wall 2, which are integral with a resilient rear yoke 3. This resilient yoke 3 biases the walls 1 and 2 to the clearance or release position of Fig. 15 5, in which top wall 2 is inclined to bottom wall 1. The walls 1 and 2 are provided with the usual 20 front parallel transverse flanges F and with the usual rearwardly divergent transverse flanges Fa. Each wall 1 and 2 has a pair of front parallel flanges F and a pair of rearwardly divergent flanges Fa.

The hookless fasteners are not shown, because 25 they are well known. These hookless fasteners are attached in respective longitudinal rows to longitudinal stringers or longitudinal adjacent portions of the fabric of the garment or other article, in the well-known manner.

When the slide is moved rearwardly, that is, in 30 the upward direction as viewed in Figs. 1 and 2, the rearwardly divergent flanges Fa interlock the hookless fasteners in the well-known manner, and the parallel flanges F operate as guides in the well-known manner.

These details are disclosed in the annexed 35 model of the invention, which is made a part of this application.

The transverse pin P has a cylindrical head 4, and a cylindrical shank 6 which is integral with head 4. Said cylindrical shank 6 has a reduced and integral cylindrical extension 7. The bottom or inner face of head 4 has diametrical recesses 5. The top face of head 4 is planar, and its bottom face is also planar and parallel to said top face, save where the recesses 5 are provided in said bottom face of head 4.

The pull-member 8 has a body 8a of planar 40 shape, which has a hole 9. Said body 8a has integral cylindrical lateral flugs 10 which interfit with recesses 5.

Said pull-member 8 optionally has an integral 45 locking prong 11, which may be omitted.

As shown in Fig. 2, the top longitudinal wall 2 has a hole or bore 12; a longitudinal and rearwardly tapered recess 14 which is longitudinally 50 disposed and located rearwardly of bore 12; a front rearwardly tapered recess 15 which is longi-

tudinally disposed and which is located in front of bore 12, and lateral recesses 16 and 17 and a hole or cut-out 18.

The front recess 15 is deeper than rear recess 14. The longitudinal recesses 14 and 15 have a common longitudinal axis which intersects the center of bore 12. The lateral recesses 16 and 17 are of the same width and depth and they have a common lateral axis which intersects the center of bore 12. This lateral axis of recesses 16 and 17 is perpendicular to the longitudinal axis of recesses 14 and 15. The formation of the cut-out 18 is optional, and this cut-out is omitted if prong 11 of the pull-member 8 is omitted.

Said top wall or outer wall 2 is also provided at its top face with integral raised stops 19 and 20.

The bottom wall 1 has a transverse hole which extends into a recess 21 of bottom wall 1.

The walls 1 and 2 can be shaped as above described by cutting and bending and stamping or coining suitable blanks. The pull-member 8 can be shaped by stamping or coining a flat blank and the pin P can be shaped by coining or pressing a cylindrical blank.

In order to assemble the parts, the cylindrical lugs 10 are interfitted with the part-cylindrical recesses 5, and the cylindrical shank 6 is inserted through hole 12 of wall 2 and the transversely aligned hole of wall 1, so that the reduced extension 7 is located in recess 21. Said reduced extension 7 is then enlarged by spinning the metal of extension 7 or in any other manner, to provide a head 7a in recess 21. The pull-member 8 is turnable relative to pin P about a pivot axis which is perpendicular to the axis of pin P.

The transverse pin P is thus turnably assembled with walls 1 and 2, so that pin P can turn easily around its pivot axis relative to walls 1 and 2. The head 4 is sufficiently close to outer wall 2 in the assembled device, so that the pull-member 8 is maintained assembled with pin P. The pull-member 8 is easily turnable relative to head 4, around the common axis of cylindrical lugs 10.

When the pivot axis of pull-member 8 is laterally disposed, as shown in Figs. 1 and 4, the cylindrical lugs 10 are partially located in the lateral recesses 16 and 17, and the optional prong 11 is aligned with the optional opening or cut-out 18. One lug 10 then abuts the stop 20. The lugs 10 then cooperate with recesses or indentations 16 and 17 to keep the longitudinal walls 1 and 2 in the parallel, normal relation shown in Fig. 4. In this relation, the walls are in selected proximate position.

The slide then operates in the usual manner. When the slide is moved longitudinally rearwardly in the locking direction, said slide interlocks the two rows of hookless fasteners. When the slide is moved longitudinally forwardly in the unlocking direction, the shank 6 of pin P disengages the hookless fasteners.

When a jam or obstruction occurs, the pull-member 8 is turned from its horizontal position of Fig. 1 to a vertical position, and said pull-member 8 and the transverse pin P are turned in unison clockwise through an angle of 90° until the respective lug 10 abuts the stop 19. One lug 10 is then aligned with the shallow rear recess 14, and the other lug 10 is then aligned with the deep front recess 15. The pivot axis of pull-member 8 is then longitudinally disposed.

The resilient rear yoke 3 then springs the walls 1 and 2 away from each other from their selected

proximate positions of Fig. 1 and Fig. 4, as illustrated in Fig. 5.

When the walls 1 and 2 are in their release positions or selected transverse positions of Fig. 5, the flanges F and Fa may clear the hookless fasteners. In such case, the slide may be moved longitudinally rearwardly relative to the hookless fasteners, without interlocking the hookless fasteners, while walls 1 and 2 are in their relative inclined positions of Fig. 5.

However, it is preferred that the flanges of walls 1 and 2 should not be moved out of engagement with the hookless fasteners when said walls 1 and 2 are in their relative release positions or selected transverse positions of Fig. 5. In such case, the flanges Fa will still interlock the hookless fasteners when the slide is moved longitudinally rearwardly in the locking direction.

However, when the walls 1 and 2 are in said release positions, the slide can be moved forwardly in the longitudinal unlocking direction. The walls 1 and 2 are sufficiently spaced apart so that the shank 6 of pin P can then disengage the hookless fasteners, even if there is a jam or obstruction forwardly of shank 6.

A great economy in manufacture and assembly is thus produced, because the lugs 10 operate as cam members, in addition to providing a turnable connection between pin P and pull-member 8. The lugs 10 may be aligned with recesses 16 and 17 in final assembled position while the extension 7 is enlarged to form head 7a, so that these small parts are very accurately assembled.

If the prong 11 and cut-out 18 are used, and the pull-member 8 is moved to its horizontal position of Fig. 1, said prong 11 is passed through cut-out 18 to engage a hookless fastener or the fabric between adjacent hookless fasteners or any part of the fabric of the garment or other article, to hold the slide against longitudinal movement.

In order to limit the movement of walls 1 and 2 towards each other when the pull-member 8 is disposed as shown in Figs. 1 and 2, the slide is provided with longitudinal tongues 22 at each longitudinal edge thereof. Said tongues 22 are integral with yoke 3 and said tongues 22 are located longitudinally between walls 1 and 2, adjacent the longitudinal edges of said walls.

The pull-member 8 operates as a control-member and it need not necessarily be a pull-member.

While I have disclosed cylindrical lugs 10 and entrant parts 16 and 17 as cam means for holding the walls 1 and 2 in their normal operating positions of Figs. 1 and 4, the invention is not limited to this type of cam means.

In general, the invention includes a device wherein a control member is connected to a turnable transverse pin, said connection between said control member and said pin being turnable or non-turnable, and said control member has a control parts or parts which cooperate with a selected first part of the adjacent slide-walls to hold the slide-walls in normal operating position in a first selected position of said turnable pin, and said control part or parts and a second selected part of said slide-wall are shaped to permit the slide-walls to move away from each other and out of said normal operating positions in a second selected position of said turnable pin. The control part or parts are located between the head of the control pin and the respective adjacent slide-wall. Since the control member is held in the first selected position, abutting the first selected part of the slide-wall, when the

connection between the pin and the inner slide-wall is completed, this provides a gauge for accurately making such completed connection by spinning the extension 7 to form inner head 7a.

It is desirable to form the enlargements 1a by spinning, in order to eliminate excessive pressure upon the assembled pin P and the control member 8, in the direction of the transversely disposed axis of the pin P.

It is preferred to have the part-cylindrical lugs 10 partly located in the recesses 16 and 17, when the final assembly is made by forming the enlargement 1a. However, the invention is not limited to this feature because the lugs 10 may abut any part of the top or outer face of the outer wall 2, when such final assembly is made. When the final assembly is made, the lugs 10 which then abut the top or outer face of the top wall 2, act as a gauge in regulating the formation of the enlargement 1a in the recess 21.

I have disclosed a preferred embodiment of my invention but numerous changes and omissions and substitutions and additions can be made without departing from the scope of my invention.

I claim:

1. A slide having V-shaped channels for engaging and disengaging longitudinally disposed hookless fasteners, said slide having longitudinal top and bottom walls, said walls having front and rear ends, said rear ends being integral with a resilient rear transverse yoke which biases said walls transversely away from each other to selected separated positions, holding means comprising a pin which is turnably connected to the bottom wall of said slide and which extends through an opening in the top wall of said slide and which is turnable about the axis of said pin relative to said walls, said holding means being operative to force said longitudinal walls towards each other from said selected separated positions to selected proximate positions and to release said walls to permit them to move to said selected transverse positions, said walls being closer to each other in said selected proximate positions than in said selected separated positions, said holding means being located and operative to separate said hookless fasteners when said slide is moved longitudinally forwardly, and a turnable member which is turnably connected to said pin to turn relative to said pin about a pivot axis which is perpendicular to the axis of said pin, said turnable member having cam means which abut the top face of said top wall when said pivot axis is laterally disposed to hold said walls in said selected proximate positions, said cam means being shaped to permit said walls to move to said selected separated positions when said pivot axis is longitudinally disposed.

2. A slide for hookless fasteners, said slide having longitudinal top and bottom walls whose rear ends are connected by a rear transverse resilient yoke which biases said walls transversely away from each other to selected separated positions, a transverse pin which is turnably connected to said bottom wall and which extends transversely through a hole in said top wall, said pin being turnable about a transverse axis, said pin having a head which is located above said top wall, said head having a bottom face which is provided with diametrical recesses, a turnable member which has lugs which are located partially in said recesses, said turnable member being turnable relative to said pin about a pivot axis which is perpendicular to said pin, the top face of said top wall having lateral recesses on opposite sides

of said hole and having longitudinal recesses on opposite sides of said hole, said lugs being shaped to partially enter said recesses, said lugs and lateral recesses being shaped to hold said walls in selected proximate positions when said lugs are located in said lateral recesses, said lugs and said longitudinal recesses being shaped to permit said yoke to move said walls to said selected transverse positions when said lugs are in said longitudinal recesses, said walls being transversely closer to each other in said selected proximate positions than in said selected transverse positions.

3. A slide for longitudinally disposed hookless fasteners, said slide having longitudinal bottom and top walls, said walls being separated at their front ends and being connected at their rear ends to a transverse resilient yoke which biases said walls transversely away from each other to selected separated positions, said walls having transverse flanges which are rearwardly divergent, a transverse pin which is located forwardly of said yoke and rearwardly of the front ends of said flanges, said pin being turnable relative to said longitudinal walls about a pin axis which is transverse relative to said longitudinal walls, said pin having a bearing in said bottom wall and extending transversely through a hole in said top wall beyond said top wall and being immovable relative to said bottom wall in a transverse direction, a control member which is turnably connected to said pin above said bottom wall, said control member being turnably connected by connecting means to said pin to turn relative to said pin about a pivot axis which is perpendicular to said pin axis, said control member being turnable in unison with said pin about said pin axis to a holding position in which said pivot axis is laterally disposed and to a release position in which said pivot axis is longitudinally disposed, said control member having a wall-operating member which is shaped and located to abut the top face of said top wall, said wall-operating member and top face being shaped to abut each other and to hold said longitudinal walls in selected proximate positions when said pivot axis is laterally disposed, said longitudinal walls being closer to each other in said selected proximate positions than in said selected separated positions, said wall-operating member being shaped to permit said rear yoke to move said walls to said separated positions when said pivot axis is longitudinally disposed.

4. A slide for longitudinally disposed hookless fasteners, said slide having longitudinal bottom and top walls, said walls being separated at their front ends and being connected at their rear ends to a transverse resilient yoke which biases said walls transversely away from each other to selected separated positions, said walls having transverse flanges which are rearwardly divergent, a transverse pin which is located forwardly of said yoke and rearwardly of the front ends of said flanges, said pin being turnable relative to said longitudinal walls about a pin axis which is transverse relative to said longitudinal walls, said pin having a bearing in said bottom wall and extending transversely through a hole in said top wall beyond said top wall and being immovable relative to said bottom wall in a transverse direction, a control member which is turnably connected to said pin above said bottom wall, said control member being turnably connected by connecting means to said pin to turn relative to said pin about a pivot axis which is perpendicular

to said pin axis, said control member being turnable in unison with said pin about said pin axis to a holding position in which said pivot axis is laterally disposed and to a release position in which said pivot axis is longitudinally disposed, said control member having a wall-operating member which is shaped and located to abut the top face of said top wall, said wall-operating member and top face being shaped to abut each other and to hold said longitudinal walls in selected proximate positions when said pivot axis is laterally disposed, said longitudinal walls being closer to each other in said selected proximate positions than in said selected separated positions, said wall-operating member being shaped to permit said rear yoke to move said walls to said separated positions when said pivot axis is longi-

10

15

tudinally disposed, said pin having an enlarged head at its top, said head having diametrical recesses at its bottom face, said connecting means being lugs which are turnably located in said recesses and which abut said top face of said top wall in all positions of said pin, said lugs also constituting said wall-operating member.

SAMUEL J. LACKRITZ.
